UNITED STATES PATENT OFFICE.

CLARENCE E. HAWKE AND BOYD M. JOHNSON, OF METUCHEN, NEW JERSEY, AS
SIGNORS TO THE CARBORUNDUM COMPANY, OF NIAGARA FALLS, NEW YORK, A
CORPORATION OF PENNSYLVANIA.

FURNACE.

Application filed February 16, 1924. Serial No. 693,232.

To all whom it may concern:

Be it known that we, CLARENCE E. HAWKE and BOYD M. JOHNSON, citizens of the United States, residing at Metuchen, in the county of Middlesex and State of New Jersey, have invented a new and useful Improvement in Furnaces, of which the following is a full, clear, and exact description.

The present invention relates to furnaces or ovens of the indirectly heated type, and more particularly to furnaces or ovens of this type which are employed for the enameling of iron and steel and for the heat treatment of ceramic ware and similar articles.

The general purpose of the invention is to provide a furnace construction in which the energy derived from the combustion of the fuel may be utilized to the maximum extent and in which the refractories are not subjected to excessive heat conditions or temperature changes. To this end we provide a furnace construction embodying a main heating chamber and a pre-heating chamber and employ silicon carbide radiating combustion chambers to heat, partially by direct and partially by indirect radiation, the ware in the main heating chamber and utilize the waste gases from said combustion chambers to heat the pre-heating chamber and the floor of the main heating chamber.

The nature of the invention will be better understood by reference to the accompanying drawings, in which we have illustrated a preferred embodiment thereof, it being understood that changes may be made in the construction shown without departing from the spirit of the invention or scope of the appended claims.

In the drawings:

Figure 1 is a front elevation of the furnace;

Figure 2 is a transverse sectional view on line II-II of Figure 3;

Figure 3 is a sectional plan view on line III-III of Figure 2;

Figure 4 is a sectional plan view on line IV-IV of Figure 2;

Figure 5 is a longitudinal sectional view on line V-V of Figure 2;

Figure 6 is a longitudinal sectional view on line VI-VI of Figure 2;

Figure 7 is a transverse sectional view on line VII-VII of Figure 3;

Figure 8 is a longitudinal sectional view on line VIII-VIII of Figure 3; and

Figures 9 and 10 are detail views illustrating the manner of operating the dampers controlling certain of the flues simultaneously with the opening and closing of the door of the pre-heating chamber.

In the illustrative embodiment of the invention, the furnace comprises a main heating chamber 2 and a pre-heating chamber 3 constructed of fire brick in the usual manner. Within the main heating chamber adjacent the opposite sides thereof are arranged two radiating combustion chambers 4, the walls of which are formed of silicon carbide. Each combustion chamber is divided into an upper half and a lower half by a horizontal partition wall extending from the front end of the chamber nearly to the rear end thereof. The upper half of each chamber has a burner opening 6 in the front end thereof into which projects an oil burner 7 supplied with oil through a pipe 8 and with primary air through a pipe 9, secondary air being supplied through a pipe 10. In order to reduce the amount of direct radiation of heat to the ware from the combustion chambers and make the temperature conditions within the heating chamber more uniform, a silicon carbide baffle wall 11 is provided intermediate each combustion chamber and the space occupied by the ware, these baffle walls being formed with spaced openings 12 therein.

The floor 13 of the main heating chamber is constructed of silicon carbide brick and directly beneath this floor is a wide flue 14 with the forward end of which the forward end of the lower half of each combustion chamber communicates, the flue having baffles 15 therein. The rear end of the flue 14 is connected to a stack 16 through a lower flue 17, while an upper flue 18 connects it with a flue 19 extending beneath the floor of the pre-heating chamber. Another flue 20 extends beneath the floor of the pre-heating chamber parallel to the flue 19 and communicates with the stack 16 through a flue 21. The floor of the pre-heating chamber is provided with openings 22 therein permitting

the waste gases flowing through the flue 19 to pass to the flue 20 through the pre-heating chamber. The lower flue 17 is controlled by a damper 23 and the upper flue 18 by a damper 24.

The dampers 23 and 24 are arranged to be operated simultaneously with the opening and closing of the door 25 of the pre-heating chamber in such manner that when 10 said door is moved to open position, the damper 24 descends and closes the flue 18, while the damper 23 simultaneously rises and opens the flue 17. This places the flue 14 beneath the main heating chamber in direct 15 communication with the stack when the door of the pre-heating chamber is open. When the door of the pre-heating chamber is closed, the damper 23 descends and closes the flue 17, while the damper 24 rises and 20 opens the flue 18, so that when the door of the pre-heating chamber is closed, the flue beneath the main heating chamber is in communication with the stack through the 25 pre-heating chamber.

Referring to Figures 8, 9 and 10, the door 25 is counter-balanced by weights 26 connected to the door by a cable 27 passing over sheaves 28 and 29. The sheave 28 is fixed to a shaft 30 journaled in bearings 31 30 carried by vertical members 32 at the rear end of the furnace. It will be apparent that when the door 25 is raised or lowered, the cable 27 will rotate the sheave 28 and shaft 30. This shaft drives a parallel shaft 33 35 through a sprocket chain 34 and sprocket wheels 35 and 36 mounted upon the respective shafts. A rope 37 connects the damper 23 to a drum 38 on the shaft 33, while a similar rope 39 connects the damper 24 to a 40 similar drum 40 on said shaft, the ropes 37 and 39 being wound about said drums in opposite directions. Each of these ropes passes between a pair of guide pulleys 41.

The travel of the combustion gases is as 45 follows: These gases flow back through the upper half of each combustion chamber and return through the lower half and then pass downwardly into the flue 14 beneath the main heating chamber, their travel through 50 this flue being retarded by the baffles 15. If the door of the pre-heating chamber is closed, the waste gases pass through the upper flue 18 into the flue 19 beneath the floor of the pre-heating chamber and then 55 pass through the openings 22 above said flue into the pre-heating chamber. After circulating in said chamber, the gases pass into the flue 20 beneath the floor of said chamber and then to the stack. On the other 60 hand, if the door of the pre-heating chamber is open, the waste gases pass from the flue 14 directly to the stack through the lower flue 17.

The reason for by-passing the waste gases 65 directly to the stack when the door of the

pre-heating chamber is open, is to prevent the cutting down of the draft on the combustion chambers which would result when said door is open if no such provision for by-passing the waste gases were made. In 70 that case the waste gases would not flow into the pre-heating chamber upon opening of the door thereof because the stack pull would be on the pre-heating chamber and cold air would be pulled to the stack 75 through the open door of the pre-heating chamber, thereby cutting off the draft from the combustion chambers. This would cause a building up of pressure on the combustion chambers and consequent leakage 80 into the heating chamber. The provision for by-passing the gases in this manner is also advantageous in starting up the furnace in that a proper draft is provided to effect a preliminary heating of the combustion chambers. After the furnace is well up to heat, the by-pass flue 17 may be closed by its damper 23 and the flue 18 is opened. 85

The great advantage of a construction as above described is in its fuel economy. Not 90 only does it utilize silicon carbide combustion chambers in a very efficient and practical manner, so that either by direct or indirect radiation a large percentage of the heat initially generated is radiated to the 95 ware, but in addition to this, the waste gases are further utilized not only for heating the floor of the main heating chamber, but for heating the pre-heating chamber. The baffle walls within the main heating chamber cut 100 down the amount of direct radiation of heat to the ware from the combustion chambers and make the temperature conditions within the heating chamber more uniform. On the other hand, heat from the combustion 105 chambers is conducted through these baffle walls very rapidly, since carborundum has a thermal conductivity about five times that of the usual fireclay refractories and its emissivity factor is about twice that of such 110 fireclay refractories. Furthermore, by reason of the fact that the floor of the heating chamber, which also forms the top wall of the waste heat flue beneath said chamber, is constructed of carborundum bricks, a relatively 115 large proportion of the heat of the waste gases passing through the waste heat flue is conducted through the floor of the heating chamber to heat the bottom of said chamber. The heat remaining in such gases after passing through the waste heat flue is largely given up in heating the pre-heating chamber and the material placed therein, so that when the waste gases pass from said chamber to the stack, they retain a relatively 120 small proportion of their original heat. The furnace has shown in actual operation a fuel consumption far below the best results heretofore attained in silicon carbide muffle 125 furnaces. 130

In muffle furnaces in common use of the combustion type, the combustion chamber is generally underneath the floor of the heating chamber and the combustion gases are circulated around the heating chamber through the flues in the side walls. This entails an expensive refractory construction, because the refractories, in order to conduct heat properly, must necessarily be made in very thin sections. In such constructions, the muffle tile have to be removed at intervals. On the other hand, in a construction such as herein disclosed, it is apparent that the furnace structure should last indefinitely as it can be built up of stock sizes in a very solid manner and none of the refractories are subjected to excessive heat conditions or temperature changes.

We claim:

- 20 1. A furnace, comprising a heating chamber having a combustion chamber associated therewith, a pre-heating chamber, a pair of flues beneath the floor of said pre-heating chamber and each having its top wall formed thereby, said top walls having openings therein establishing communication between said flues and pre-heating chamber, and means for conducting the waste gases from said combustion chamber to one of said flues and for conducting them from the other of said flues out of the furnace, substantially as described.
- 25 2. A furnace, comprising a heating chamber, a combustion chamber having a silicon carbide partitioning wall between it and the heating chamber, a waste heat flue beneath

the floor of said heating chamber and having its top wall formed thereby, said top wall being constructed of silicon carbide, a pre-heating chamber, and a flue beneath the 40 floor of said pre-heating chamber and adapted to receive the waste gases from the flue beneath the heating chamber, the top wall of the flue beneath the pre-heating chamber being formed by the floor of said chamber, substantially as described.

3. A furnace, comprising a heating chamber having a combustion chamber associated therewith, a pre-heating chamber having a door, and means acting automatically to 50 admit the waste gases from the combustion chamber to the pre-heating chamber when the door is closed and to exclude such gases therefrom when the door is opened, substantially as described.

4. A furnace, comprising a heating chamber having a combustion chamber associated therewith, a pre-heating chamber having a door, a stack, a flue for conducting the waste gases from said combustion chamber directly to said stack, a second flue for conducting such gases into said pre-heating chamber, a damper for controlling each of said flues, and damper-operating means acting to automatically close the first flue and open the 60 second when the door is closed and to open the first flue and close the second when the door is opened, substantially as described.

In testimony whereof we have hereunto set our hands.

CLARENCE E. HAWKE.
BOYD M. JOHNSON.
